UNITED STATES PATENT OFFICE.

HERMANN ALEXANDER BRACKELSBERG, OF HAGEN, GERMANY.

APPARATUS FOR WASHING ORE.

1,080,886.

Specification of Letters Patent.

Patented Dec. 9, 1913.

Application filed July 2, 1913. Serial No. 776,960.

To all whom it may concern:

Be it known that I, HERMANN ALEXANDER BRACKELSBERG, a subject of the German Emperor, and resident of Karlstrasse 1, Hagen, 5 Germany, have invented certain new and useful Improvements in Apparatus for Washing Ore, of which the following is a specification.

My invention relates to apparatus for 10 washing ore by the well known method of floating off the gangue. In some instances oil or the like is added so as to render the sulfid particles capable of floating, or the dry ore is spread on a water surface. With 15 the last method good results are obtained only when the particles are separately or loosely delivered on the water surface at a correct angle thereto. For this purpose it is necessary to constantly renew the surface 20 of the water, to deliver the particles separately and prevent their floating together or coming against any obstacle on the surface of the water. Various devices have previously been adopted for fulfilling either the 25 one or the other condition, but no means have been able to satisfy all the requirements.

It is the object of my invention to provide 30 an apparatus which is capable of effecting complete separation of the metallic parts from the gangue and the delivery of each constituent into separate collecting spaces, whereby unavoidable middle product is obtained which can be subsequently treated.

35 This improved apparatus consists in an arrangement wherein the ore is freely discharged from a superposed hopper onto a distributing device (cone-surface) along which it descends and spreads onto a lower 40 cone-surface where it becomes moistened and further scattered after which it dribbles into the overflow separators, one after another, for dividing and collecting the different sorts of constituents as sediments while the 45 gangue flows off with the tail water through a channel connected with the last separator.

The apparatus is shown in sectional elevation, by way of example, in the accompanying drawing.

50 The frame 1 has bearings 2 and 3 for a vertical shaft 4 which is partly bored out as at 5. On the upper portion of the shaft 4 is mounted a rotary sleeve 6 with cone 7 and said shaft 4 is rotated through the intervention 55 of the bevel gear wheels 8 and 8'. Around the cone 7 is placed a hopper 9 and the gap between the cone 7 and hopper 9

can be adjusted to various degrees by means of a nut 10 screwed upon a threaded portion of the shaft 4 so as to press against the nave 60 of the wheel 8'.

Beneath the lower end of the cone 7 and its surrounding hopper 9 is fixed on shaft 4 a distributing cone 11 which partially extends into the cone 7 and which serves also 65 as a water-container. The interior of the distributor 11 communicates with the bore 5 of the shaft 4 and receives water from the latter from the supply pipe 12. The bottom portion of the distributor 11 has a plurality 70 of holes 11' near the periphery from which the water runs in fine jets, the internal upper portion of said distributor providing an air cushion.

The lower edge of the distributor 11 extends over a cone-shaped spreader 13 which is also fast on the shaft 4. The water from the distributor forms a sheet of water over the surface of the spreader 13 and runs off uniformly at the lower edge thereof. The 80 dry raw material from the hopper 9 falls onto the distributor 11 and is delivered onto the running water of the spreader 13 where it becomes moistened and scattered apart.

Around the spherical head of the foot 85 bearing 3 of the shaft 4 is mounted the lower cylindrical portion of a funnel-shaped overflow separator 14 which is so arranged that the upper edge projects a little above the lower edge of the distributor 13, screws 15 90 being provided for accurately leveling said upper edge. On the exterior of the cylindrical portion conveniently near the lower end of the separator 14 is fixed a spherically-headed fitting 16 for sustaining a second 95 funnel-shaped overflow separator 17, the upper rim of which is lower than that of the separator 14 and can be horizontally adjusted by means of screws 18. The separator 17 is fitted with an outer vessel 19 having an 100 upper cylindrical portion and a lower conical portion. The rim of the vessel 19 is lower than that of the separator 17 and is fitted with a circular discharge channel 20. Between the separator 17 and vessel 19 there 105 is provided a funnel 21 open at top and bottom forming a circular conical space around the separator 17 which at the lower end opens freely into the vessel 19, while the upper rim of said funnel 21 projects above 110 that of 19 but lies below that of 17.

The operation is as follows:—The water supplied through the pipe 12 and bore 5 into the distributor 11 compresses the air in

the latter so as to provide an air cushion which regulates the outflow from the perforations 11¹ to a steady uniform film over the entire surface of the spreader 13 from 5 which it runs off into the separator 14 in a radial direction and slowly over the rim of the latter, then creeping along the outer surface of 14 into the separator 17. When the latter is full, the water flows over the rim 10 thereof into the funnel 21 which fills the vessel 19 from which it overflows into the channel 20 with the difference, however, that no radial flow takes place from 17 toward the rim 19 by reason of the projecting rim of 15 the funnel 21. The sludge will pass down the funnel into the lower part of the vessel 19 where it will gradually rise and finally overflow the rim.

When all the parts 14, 17 and 19 have been 20 filled and the hopper 9 has been charged with the reduced materials, the regulating cone 7 is set revolving and adjusted by means of the nut 10 so as to supply a steady 25 circular delivery of material onto the distributor 11 with a free vertical fall from the lower edge of 7 to the suitably distanced surface of 11. This free fall causes any ordinary dust to separate from the materials and thereby render the useful constituents 30 more susceptible to the action of the water during the short transit between the spreader 13 and first separator 14. After the free fall from 7 to 11, the materials slide straight down while at the same 35 time gradually separating laterally on the widening surface of the cone 11. The material then falls onto the cone 13 in a well prepared condition for the preliminary moistening by the gentle flow of water from the holes 11¹ at the underside of 11. Along the cone 13 the material becomes still further separated or spread out until it reaches the 40 surface of the water in the vessel 14.

The heavier particles which contain no ore 45 fall to the bottom of the first separator 14 from where the same can be removed through a sliding door 22. The floating ores and gangue such as quartz, which have become but little moistened down the cone 13, 50 are driven by the radial flow of the water over the rim of 14 and slide along the exterior surface until they meet at an acute angle *l m n* the water level in the separator 17. This is an important arrangement and 55 causes the separation of the earthy matter and the lean ore, which falls to the bottom of the vessel 17, from the ore which is still dry and floats in radial direction toward and over the rim of the vessel 17 into the next 60 vessel 21. The vessel 17 can be cleared out through a door 23.

A similar operation could be repeated by providing suitable multiplicity of vessels, but in practice it has been found that the two vessels 14 and 17 and the duplex overflow suffice for all purposes. The separated ore is therefore allowed to fall into the annular space between 17 and 21 and finally reach the bottom of the vessel 19 from which it can be withdrawn through the door 24. 70 The clear water ascends in the vessel 19 and finally runs off into the channel 20.

What I claim as my invention and desire to secure by Letters Patent is:—

1. In a float separator for minerals, a plurality of receptacles adapted to overflow into one another, the overflow walls being at progressively lower levels, and each overhanging the surface of liquid in the next receptacle at an angle adapted to cause a film of liquid to flow along the overhanging surface of said wall, and means for gently feeding the material and liquid across the series of receptacles. 75

2. In a float separator for minerals, a plurality of nested receptacles adapted to overflow into one another, the overflow walls being at progressively lower levels, and each overhanging the surface of liquid in the next receptacle at an angle adapted to cause a film of liquid to flow along the overhanging surface of said wall, and means for simultaneously feeding liquid and material to be separated across the series of receptacles. 85

3. In a float separator, a receptacle adapted to contain liquid and present an exposed surface thereof, means for feeding a layer of liquid and material, to be separated thereto, consisting of an overflow wall overhanging the surface of the liquid in the receptacle, at an inclination adapted to cause the overflowing material to flow along the overhanging walls. 90

4. In a float separator for minerals, a plurality of nested receptacles adapted to overflow into one another, and present an exposed surface, means for feeding a layer of liquid and material to be separated to the said receptacle consisting of an overflow wall overhanging the surface of the liquid in the said receptacles at an inclination adapted to cause the overflowing material to flow along the overhanging walls. 100

In testimony whereof I have hereunto signed my name this 20th day of June, 1913, in the presence of two subscribing witnesses.
